US0D1034341S

(12) **United States Design Patent** (10) Patent No.: **US D1,034,341 S**
(45) Date of Patent: ** Jul. 9, 2024

(54) **RADIATOR GRILLE FOR VEHICLE**

(71) Applicant: **VOLKSWAGEN AKTIENGESELLSCHAFT, Wolfsburg (DE)**

(72) Inventors: **Felipe Montoya Bueloni, Wolfsburg (DE); Thiago Carfi Do Rosario Pinho, Wolfsburg (DE)**

(73) Assignee: **VOLKSWAGEN AKTIENGESELLSCHAFT, Wolfsburg (DE)**

(**) Term: **15 Years**

(21) Appl. No.: **29/863,570**

(22) Filed: **Dec. 20, 2022**

(30) **Foreign Application Priority Data**

Jul. 20, 2022 (WO) WIPO120375
